UNITED STATES PATENT OFFICE.

JONAS NORTHROP, OF HOPEDALE, MASSACHUSETTS, ASSIGNOR TO DRAPER COMPANY, OF HOPEDALE, MASSACHUSETTS, A CORPORATION OF MAINE.

FILLING-REPLENISHING LOOM.

SPECIFICATION forming part of Letters Patent No. 718,575, dated January 13, 1903.

Application filed February 3, 1902. Serial No. 92,423. (No model.)

To all whom it may concern:
Be it known that I, JONAS NORTHROP, a subject of the King of Great Britain, and a resident of Hopedale, county of Worcester, State 5 of Massachusetts, have invented an Improvement in Automatic Filling - Replenishing Looms, of which the following description, in connection with the accompanying drawings, is a specification, like characters on the drawings representing like parts.

Looms provided with automatic filling-replenishing mechanism of the type shown in United States Patent No. 529,940, wherein a fresh supply of filling is inserted when required in the running shuttle, necessitate the employment of a shuttle which can be automatically threaded, and various forms of shuttle-threading means have been devised. The most successful of such devices in actual practice have been mounted directly upon the shuttle and have operated to direct the filling-thread toward the delivery-eye as the shuttle is shot across the loom from the replenishing side, completion of the threading being effected upon the following return shot. Such threading devices comprise, essentially, a longitudinal open thread-receiving passage, a thread-eye in the side of the shuttle and having a slot leading thereto, and a horn to direct the thread from the outer end of the passage to and down the slot into the eye, guards of various kinds being used to prevent the thread from whipping out of the thread-receiving passage.

In the replenishing mechanism of the type hereinbefore referred to the filling or thread ends are secured to a holding device, so that when filling replenishing is effected the filling end extends from such device to the filling-supply in the shuttle in an oblique line, and when the shuttle is thrown from the shuttle-box the filling or thread end enters the thread-receiving passage of the threading device if nothing occurs to prevent, though the pull of the filling will still be at an angle to the longitudinal axis of the filling-supply. Even if the filling does not enter the passage on the first pick probably no damage will be done on such pick, provided the direction of pull on the thread is not so oblique to the axis of the filling-carrier as to prevent the thread from readily drawing off over the tip thereof;

but if the obliquity is too great the thread will break, causing a mistread. If the filling or thread end does not enter the passage on the first pick, however, even though it may draw off from the supply in the shuttle, the return shot of the latter reverses the direction of pull on the filling, and as the latter draws off over the supported head end of the supply it breaks. Such mistreads require a change of filling, and manifestly a mistread and breakage of filling will inevitably occur if the thread does not enter the receiving-passage of the threading device and remain therein on the first pick after replenishing.

Each change of filling means the loss of from one to three or more picks, necessitating arrest of the take-up and a letting back corresponding to the number of lost picks in order to prevent thin places, and, other things being equal, the smaller the number of filling changes in a given time the greater will be the efficiency of the loom.

In my present invention I have provided means which reduces mistreading to such a minimum that filling replenishing due to mistreading is practically eliminated, and the efficiency of the loom is correspondingly increased.

The variations in tension, curling or twisting, and other vagaries of filling-thread well known to those skilled in weaving which tend to prevent the proper operation of shuttle-threading devices now in extended use have no effect on the operation of my present invention, which insures the certain and sure delivery of the filling whenever a fresh supply is inserted in the shuttle.

I have provided for the positive coöperation of the filling-thread and the delivery means on the shuttle at the time of filling change, so that the thread is properly delivered at the instant the shuttle leaves the replenishing side of the loom, the shuttle having a normally closed leader, through which the filling-thread passes, substantially in alinement with the longitudinal axis of the supply in the shuttle as the thread is drawn off to be delivered, and this leader is opened at the time of filling replenishing long enough to receive the filling or thread end, the closing of the leader then positively preventing withdrawal of the thread and maintaining it in position to be

subjected to a direct pull. The leader is located in front of the tip end of the filling-supply, and after the thread enters the leader its proper delivery is absolutely assured on either 5 shot of the shuttle, whether the delivery is directly from the leader or from the latter to the delivery-eye of the shuttle and thence to the shed. The leader constitutes the normally closed entrance or inner end of a longitudinal 10 thread-receiving passage provided at its outer end with means to direct the thread from the passage to the side delivery-eye of the shuttle, and usually the directing of the thread to the eye is completed upon the second 15 pick after filling change. Whether this is delayed or not is of no moment in my present invention, so that the complete threading may be delayed for an indefinite number of picks without breakage of the filling or interference with its delivery, which will be 20 from the top rather than from the side of the shuttle. For general purposes the latter delivery is preferred, and for this reason I have provided means for automatically conducting 25 the thread from the leader to a side delivery-eye in the shuttle.

Various novel features of my invention will be hereinafter described, and particularly pointed out in the following claims.

30 Figure 1 is a front elevation of a portion of the replenishing side of a loom provided with mechanism for automatically inserting fresh filling in the shuttle when necessary, one form of replenishing mechanism being illustrated 35 suitable for use in connection with my present invention. Fig. 2 is a transverse sectional detail thereof on the irregular line 2 2, Fig. 1, looking toward the left, with the replenishing mechanism in normal condition. Fig. 3 is 40 a detail similar to Fig. 2, but showing the relative position of some of the parts just as the fresh supply of filling is inserted in the shuttle. Fig. 4 is an enlarged top or plan view of the thread-delivery end of the shuttle, showing 45 the means thereon whereby proper delivery of the thread is positively insured and effected after a change of filling in accordance with my invention. Fig. 5 is a longitudinal sectional detail on the line 5 5, Fig. 4, viewed 50 in the direction of arrow 55. Figs. 6 and 7 are transverse sectional views on the line 6 6, Fig. 4, looking toward the right, the thread-leader being shown closed in Fig. 6 and open in Fig. 7, ready in the latter case to receive 55 the thread of filling. Fig. 8 is a side elevation of the means (detached from the shuttle) for effecting the proper delivery of the thread, and Fig. 9 is a perspective view of the thread-delivery end of the shuttle.

60 Referring generally to Figs. 1 to 3, the loom-frame A, lay A³, slotted at 10 below one of the shuttle-boxes, as B^X, the bunter C² on the lay, and the filling-feeder F are of well-known construction, the filling-feeder consisting of two 65 disks a' a², which support between them the filling-carriers or supplies of filling b, said disks rotating in unison on a stud a, rigidly

secured to a stand A⁷, mounted on the breast-beam A⁴⁰ at the side of the loom adjacent the shuttle-box B^X. The thread or filling ends are 70 led from the tip ends of the filling-carriers over a disk b² (see dotted lines, Fig. 1) to a holding-stud b³, the latter and the disk b² rotating intermittently with the feeder to present the filling-supplies b one by one into position to be transferred to the shuttle, all substantially as shown in United States Patent 75 No. 664,790, dated December 25, 1900, the rotation of the feeder being effected herein substantially as provided for in said patent. As 80 therein shown the stand A⁷ herein is provided with a horizontal stud f, on which is loosely mounted the hub f² of the transfeerer f', extended between the disks a' a² of the feeder to engage the head of the filling-carrier to be 85 transferred, while the tip of the latter is engaged by the notched downturned end 22 of a lateral arm 21, rigidly secured to the transfeerer. When a change occurs in the condition of the filling in the shuttle, such as its 90 exhaustion to a predetermined extent or its breakage, the replenishing mechanism is automatically actuated to furnish the shuttle with a fresh supply of filling, the actuation 95 of said mechanism being effected in well-known manner by the turning of a controlling rock-shaft d' in the direction of arrow 65, Fig. 2, said rock-shaft having fast thereon an arm d^X, held in the position shown in Fig. 2 by a strong spring d³. A shuttle-feeler y^X, fulcrumed on the frame at y, is provided with a toe y', against which the arm d^X is held by the spring, the shuttle-feeler having a rigidly-connected branch y². A headed rocker-stud m¹² is mounted on the depending end f³ of the 100 transfeerer, said stud being normally turned in the direction of arrow 12 by a spring m^X, Fig. 1, and an arm m¹³, secured to the stud, has a lateral lug m¹⁴, against which the branch y² rests, and a notched dog m¹⁵ is adjustably 105 secured to the arm m¹³, the dog being moved into the path of the bunter C² when a change 110 of filling is to be effected, all as provided for in the patent referred to.

In Figs. 1 and 2 the replenishing mechanism is shown in normal position, while in Fig. 3 the parts are shown in the position assumed at the instant a filling-supply has been transferred from the feeder F and inserted in the shuttle S, the old or spent filling-carrier having been ejected from the bottom of the shuttle and through the slot 10 in the bottom of the shuttle-box B^X.

So far the mechanism described is old and not of my invention; but a general idea of the 125 operation thereof is necessary to a correct understanding of my invention.

I have attached to the downturned end 22 of the lateral arm 21 a cam-like actuator 75, which at the time a fresh supply of filling is 130 inserted in the shuttle, as shown in Fig. 3, operates to effect at such time a positive co-operation between the fresh thread end of filling and the thread-delivering means on

the shuttle, to thereby insure the proper delivery of the filling, as will now be described.

Referring now more particularly to Figs. 4 to 7, inclusive, and Fig. 9, the body of the shuttle S has a longitudinal opening s' therein to receive the filling supply or carrier b, usually in the form of a bobbin or cop, the shuttle being provided with any suitable form of holding device to grasp the head of the filling-carrier and maintain it in position in the opening s' with its tip end adjacent the delivery end of the shuttle. The shuttle wood is cut out at such end to receive the major portion of the thread-delivering means, which is preferably made as a casting comprising an elongated body 80, having a depending stud 81 to enter a hole s², Fig. 5, in the shuttle, the body having a longitudinal thread-receiving passage 82 therein formed by the upward extensions or walls 83 84 of the body, the inner faces of said walls being flared to present a wide open top for the passage. At its inner or entrance end the passage is contracted by inward bulges 83^X 84^X of the walls, and said bulges are vertically and oppositely slotted, as at 85 86, respectively, while the exterior of the wall 84 has two lateral ears 87 on opposite sides of the slot 86. (See Fig. 8.) In the bottom of the slots and crossing the passage 82 at its contracted entrance 82^X I have shown a friction-pad 88, which preferably is a piece of felt, to exert a sufficient drag or tension upon the filling-thread as it draws off through the passage, a pin 89, Figs. 6 and 7, holding the pad in place. The ears 87 have pivotally mounted between them on a pin 90 a finger-like closer or cover 91 for the entrance end of the thread-receiving passage, this entrance, with its cover, constituting a normally closed "leader," as I have termed it, located in front of the tip or delivery end of and substantially aligned with the filling-supply and through which the filling-thread is led or directed as it is drawn off to be delivered. This cover or closure 91 swings transversely to the passage 82 in the slots 85 86, and when in normal position its free end rests on the top of the pin 89, (see Fig. 6,) completely closing the leader, so that if the filling-thread is therein it cannot by any possibility fly or whip out, the leader normally being a closed eye, the cover forming a thread-retainer. In its open position, which is assumed for the admission of the thread or filling end, the cover or retainer is swung up into the slot 86, its free end then being hooded or protected by the bulge 84, so that no obstacle will be presented to entry of the thread end, the top of the slot acting as a stop for the retainer. (See Fig. 7.) The retainer has a cam-slot 92 therein eccentric to the pivot 90 and which is entered by a spring-finger 93 on a plate 94 of spring metal, herein shown as snapped into a socket s³, formed in the inner face of the shuttle-wall. Referring to Fig. 5, this plate is shown in full lines in place in the socket and in dotted lines swung

up on a retaining - rivet 95, passed through the shuttle - wall, and it will be seen that this plate is quite deeply notched longitudinally, as at 96, to permit the upper portion 97 of the plate to be bent inward to present a cam-surface 98, the finger 93 forming an extension of the cam portion, the positions of the cam portion, corresponding to closed and open positions of the retainer 91, being shown respectively in Figs. 6 and 7. Normally the resiliency of the plate 94 maintains the cam-surface projecting inward toward the longitudinal center of the shuttle, as in Fig. 8, so that the finger 93 holds the retainer with considerable force against the pin 89, effectively and positively closing the leader, the finger moving in a recessed part 840 of the wall 84, Figs. 6 to 9. If the cam-surface 98 is pressed outward, however, toward the shuttle-wall, as in Fig. 7, the finger 93 by its outward movement travels in the cam-slot 92 of the retainer 91, and thereby quickly swings the latter up and outward into the position shown in Fig. 7, opening the leader and permitting entry of a filling-thread end thereinto and into the thread-receiving passage 82.

The cam 75, hereinbefore referred to as movable with the transerrer of the replenishing mechanism, is so located that when the transerrer descends into the position shown in Fig. 3 to insert the filling-supply in the shuttle it will engage and press outward the cam-surface 98, thereby opening the leader for the reception of the filling-thread end when the filling-supply is positioned in the shuttle. No sooner does the ascent of the transerrer to normal position after transfer effect disengagement of the cam 75 and the cam-surface 98 than the latter springs inward to normal position, closing the leader with the fresh filling-thread therein before the shuttle is moved from the shuttle-box by the picking mechanism, the concavity of the retainer 91 on its lower edge assisting in depressing the thread with it should the latter be raised somewhat between the filling-supply and the disk b². The closing action of the retainer is thus an additional safeguard toward positively insuring the insertion of the thread into the leader. At the first shot of the shuttle from the replenishing side of the loom the thread draws freely through the leader and off of the tip or delivery end of the filling-supply, it being remembered that the filling end is secured to the holding-stud b³, and the first pick of fresh filling is laid, the pull on the filling through the leader being substantially in direct alinement with the axis of the filling-supply.

The threading of the filling into the usual side delivery-eye s⁴, Fig. 5, of the shuttle will now be described, it being understood that the preferable delivery-point for the thread is from the side of the shuttle nearer the fell. As the thread is already positively retained in the entrance end 82^X of the passage 82 by the leader, the travel of the shuttle away

from the filling-feeder tends to draw the thread fully into the passage throughout the length thereof and down through a narrow, slit-like, and non-vertical clearance between 5 the forwardly-extended and laterally-widened top 99 of the wall 83 and the forward extension 100 of the top 101 of the wall 84, the inner longitudinal edges of the tops being rounded to direct the thread into the passage between 10 its downwardly-converging side walls. The extension 100 is slightly overlapped by the top 99, as shown in Figs. 4, 6, and 7, to present the clearance 102, and usually on the first pick after replenishing the thread will 15 be drawn through this clearance, and then on the next or return pick the thread will be drawn down around the horn 103, which is located at the front end of the wall 84, through the slot s⁵ in the shuttle, and thence to the 20 side delivery-eye s⁴. To completely thread the shuttle is thus a progressive operation, requiring two picks at least, the term "complete threading" meaning the automatic direction of the filling-thread to the delivery-eye s⁴, and that part of the threading operation performed after the admission and retention of the thread in the leader is not broadly different from the corresponding operation in self-threading shuttles now in use. 25

30 There is this great difference to be observed, however—viz., that in my present invention if the threading of the shuttle is not "completed" in the sense heretofore noted the delivery of the thread is in no way hindered or 35 stopped, for once the thread is confined in the leader delivery can be made directly therefrom for an indefinite number of picks without affecting the proper operation of the loom—that is, the thread will draw through 40 the leader over the end of the shuttle on picks away from the replenishing mechanism and over the retainer 91 and the top of the shuttle on the opposite pick with equal freedom. On the contrary, with threading devices now 45 in use if the thread is not drawn down into the thread-receiving passage on the first pick and then around the horn and into the delivery-eye of the shuttle on the next pick the thread will be broken instantly on such second pick and a fresh supply of filling must be provided.

With my invention a misthread cannot occur on either pick, because the thread is brought into positive and deliverable coöperation with the leader as the fresh supply is 55 inserted in the shuttle and nothing is permitted to depend on the thread or its position to effect the threading of the shuttle.

The proper and uninterrupted delivery of 60 the thread from the shuttle under all conditions is the broad or generic object to be attained, and subsidiary thereto is the more specific object of action upon the filling-thread so that it will deliver from the preferable part 65 of the shuttle—viz., the side delivery-eye; and in my present invention I have attained both the generic and specific objects in a prac-

tical and simple manner. The block 80 is secured in place in the shuttle in any suitable manner, as by a transverse screw s⁶, Fig. 5, 70 inserted from the side of the shuttle. A transverse pin 104 across the bottom of the passage 82 near its front end supports the thread practically in alinement with the axis of the filling-carrier, so that a very direct pull is effected, an upright guide-pin 105 presenting a smooth surface for the thread as it turns the corner from the passage into the delivery-eye s⁴ under the heel 106 of the horn, the thread traveling through the passage 82 in a 80 path very closely approaching a straight line forming a continuation of the axis of the filling-carrier. The notch back of the heel 106 keeps the thread from jumping up out of the eye s⁴ after it has been directed thereinto. 85 The leader not only provides for a delivery of the thread whether the shuttle is completely threaded or not, but it also compels the thread to pull off from the supply in a direct line substantially in alinement with its axis, thus insuring the most perfect and advantageous 90 conditions for the thread to draw off without being subjected to undue strain.

Sometimes the thread will be thrown forward in a loop between the filling-supply and 95 the adjacent delivering means, when the shuttle is suddenly stopped at the end of its stroke, and heretofore some trouble has been experienced by the thread-loop catching over some part of the delivering means and breaking. 100 Breakage of the thread from such cause cannot occur with the structure herein shown, for if a thread-loop is formed and thrown forward it will only fall upon the closed top of the leader, or if very long the loop may drop 105 over the said closed top into the thread-passage beyond; but immediately upon the opposite throw of the shuttle the tension on the thread will take up such loop, drawing it back and through the leader without damage. 110

It is practically an impossibility for a loop to be thrown as far as the overlapped extensions 99 100, and if it should happen the beveled sides of the passage 82 would direct the loop down toward the bottom of the passage and away from the extensions. 115

The end of the supply of filling from which the thread draws off during weaving is termed the "delivery end" of the filling-supply and is so designated in some of the following 120 claims.

The portion of thread or filling which leads from the filling-supply at the time of filling replenishing, and which is brought under the control of the means for effecting delivery of the thread from the supply of filling, is termed the filling or thread end, and also the thread end of the fresh filling-supply, and is so designated in some of the appended claims. 125

I have herein shown and described one practical embodiment of my invention in the best and most satisfactory form now known to me, and accordingly I have not attempted to show or describe various changes and modifications 130

which may be made as to details of construction, arrangement, and operation which may be made by those skilled in the art without departing from the broad spirit and scope of 5 my invention.

Having fully described my invention, what I claim as new, and desire to secure by Letters Patent, is—

1. In a loom, a shuttle adapted to contain 10 a supply of filling and provided with a leader through which the thread from such supply draws to be delivered, mechanism to automatically provide the shuttle with filling, and means to open said leader to receive the thread 15 end of the fresh filling-supply, and close the leader over the said thread end.

2. In a loom, a shuttle adapted to contain 20 a supply of filling and provided with a leader through which the thread from such supply draws to be delivered, mechanism to automatically provide the shuttle with filling, means controlled by or through the operation of said mechanism to open said leader to receive the thread 25 end of the fresh filling-supply, and means to close said leader over the said thread end.

3. In a loom provided with automatic filling-replenishing mechanism, a shuttle adapted to 30 contain a supply of filling and provided with a threading device having a thread-entrance through which the thread from the supply draws to be delivered, and means to temporarily open the latter to receive the thread 35 end of the fresh filling-supply, and to close it to confine the thread end therein.

4. In a loom, a shuttle adapted to contain 40 a supply of filling, a leader on the shuttle adjacent the delivery end of the filling-supply and through which the thread from such supply draws to be delivered, mechanism to automatically provide the shuttle with filling, and means operated upon actuation of said mechanism to cause the leader to assume immediate and deliverable control of the thread 45 drawn from the fresh supply of filling.

5. In a loom, a shuttle adapted to contain 50 a supply of filling, a leader in front of and in axial alinement with the supply of filling and through which the thread draws to be delivered, mechanism to automatically provide the shuttle with filling, and means operated upon actuation of said mechanism to enable the 55 thread of the fresh supply of filling to be received by and retained in the control of the leader in readiness to be delivered.

6. In a loom provided with automatic filling-replenishing mechanism, a shuttle adapted to 60 contain a supply of filling and provided with a longitudinal thread-passage in its delivery end, a normally operative device to close the inner, or entrance, end of said passage, and means operative upon filling replenishing to move said device to open, and thereafter close, the entrance end of the passage, to permit the 65 entry thereinto of the thread end of the fresh filling-supply inserted in the shuttle.

7. In a loom, a shuttle adapted to contain 70 a supply of filling and provided with a device to deliver the thread, mechanism to automatically insert fresh filling in the shuttle, and means operated contemporaneously with filling replenishing to effect coöperation of said device with, and positive retention of, the thread end of the fresh supply of filling, to insure proper delivery thereof.

8. In a loom provided with automatic filling-replenishing mechanism, a shuttle adapted to 80 contain a supply of filling and provided with a thread-delivering device, and means operating simultaneously with said mechanism to effect positive coöperation of the said device with the thread end of the fresh supply of filling as the latter is inserted in the shuttle.

9. In a loom provided with automatic filling-replenishing mechanism, a shuttle adapted to 85 contain a supply of filling and provided with a thread-delivering device, and means actuated by and simultaneously with the operation of said mechanism to effect positive coöperation of said device with the thread end 90 of the fresh supply of filling as the latter is inserted in the shuttle.

10. In a loom, a shuttle adapted to contain 95 a supply of filling and provided with a normally closed leader through which the thread draws to be delivered, mechanism to automatically provide the shuttle with filling, and means actuated by and simultaneously with the operation of said mechanism to open the said leader to receive the thread end of the 100 filling-supply inserted in the shuttle and retain it in axial alinement with said supply.

11. In a loom provided with automatic filling-replenishing mechanism, a shuttle adapted to 105 contain a supply of filling and having at its delivery end a thread-leader provided with a movable, normally closed top, the thread passing through the leader as drawn off for delivery, and means to move the top to open the leader for the reception of the 110 filling-thread end when fresh filling is inserted in the shuttle, and thereafter to return the top to normal position to close the leader and retain the thread therein.

12. In a loom provided with automatic filling-replenishing mechanism, a shuttle adapted to 115 contain a supply of filling and provided with a normally closed thread-leader and a delivery-eye, means to open the leader upon filling replenishing, to receive the fresh-filling-thread end, and means to automatically direct the latter from the leader to the delivery-eye.

13. In a loom provided with automatic filling-replenishing mechanism, a shuttle adapted to 125 contain a supply of filling and provided with a threading device which normally permits neither admission nor withdrawal of the filling-thread, and means operative by or through actuation of the replenishing mechanism to render the threading device temporarily receptive to the admission of the fresh-

filling-thread end, return of said device to normal condition positively preventing withdrawal of the thread thereafter.

14. In a loom provided with automatic filling-replenishing mechanism, a shuttle adapted to contain a supply of filling and provided with a side delivery-eye and a thread-retaining leader in front of the delivery end of the filling-supply, means to open and close the leader by and simultaneously with the operation of the replenishing mechanism, to effect the entrance and positive retention of the fresh-filling-thread end in the leader, and means to thereafter automatically direct the thread from the leader to the side delivery-eye.

15. In a loom provided with automatic filling-replenishing mechanism, a shuttle adapted to contain a supply of filling and provided with a side delivery-eye, and a thread-retaining leader in front of the delivery end of the filling-supply, means mounted independently of the shuttle to effect the opening and closing of the leader upon filling replenishing, to receive and thereafter retain in the leader the fresh-filling-thread end, and means carried by the shuttle to thereafter direct the thread from the leader to the delivery-eye of the shuttle.

16. In a loom, filling-replenishing mechanism, a shuttle adapted to contain a supply of filling and provided with an automatically self-threading device having a normally closed entrance for the thread to lead through as drawn off from the filling-supply, and means operative upon actuation of said mechanism to temporarily open said entrance for the admission of the fresh-filling-thread end, subsequent closure of the entrance positively retaining the thread therein.

17. In a loom, filling-replenishing mechanism, a shuttle adapted to contain a supply of filling and having a side delivery-eye, threading means on the shuttle, including a longitudinal thread-passage, a device to automatically direct the thread therefrom to the delivery-eye, and a device to normally bridge the inner end of the passage, and means to positively move said device to temporarily open the inner end of the passage when a fresh supply of filling is inserted in the shuttle, to receive the thread thereof, return of said device to normal position closing the end of the passage with the thread positively retained therein.

18. In a loom, automatic filling-replenishing mechanism, including a transerrer to transfer filling-supplies one by one to the shuttle, a shuttle adapted to receive and hold a filling-supply and having a leader for the filling-thread as drawn off from the supply, a device on the shuttle to effect opening and closing of the leader, and means actuated by transferring action of the transerrer to operate said device to open the leader for the admission of the fresh filling-thread.

19. In a loom provided with automatic fill-

ing-replenishing mechanism, a shuttle adapted to contain a supply of filling and provided with a thread-leader having an open top and located in front of the delivery end of the filling-supply, a transversely-movable cover for and to close the top of the leader, a spring to normally maintain the cover in closed position, and means operative by or through actuation of the replenishing mechanism to move the cover, through its spring, to thereby open the leader for the admission of the fresh filling-thread.

20. A shuttle for automatic filling-replenishing looms, having an opening to receive a supply of filling, a leader at the end of said opening adjacent the delivery end of the filling-supply, to receive and direct the filling-thread drawn from the supply, and a device to normally close the leader positively, to surround and prevent escape of filling-thread.

21. A shuttle for automatic filling-replenishing looms, having an opening to receive a supply of filling, and a side delivery-eye, and threading means for the shuttle, located at one end of said opening, said means including a leader through which the thread passes from the filling-supply, a normally operative, movable closure for the leader, to prevent escape of the thread therefrom, and a device to direct the thread from the leader to the delivery-eye.

22. A shuttle for automatic filling-replenishing looms, having a longitudinal opening therein to receive a supply of filling, and a side delivery-eye, and means mounted on the shuttle to automatically effect proper thread-delivery, said means including a longitudinal thread-receiving passage having a normally closed inner end or entrance, a movable closing device therefor, a spring on the shuttle to normally maintain said device in closed position, and a horn at the outer end of passage to direct the thread therefrom to the delivery-eye.

23. A shuttle for automatic filling-replenishing looms, having an opening to receive a supply of filling, a longitudinal thread-receiving passage having a normally closed entrance between it and said opening, a device movable transversely of the passage to close the entrance thereof, and yielding means to normally maintain said device in position to close the entrance.

24. A shuttle for automatic filling-replenishing looms, adapted to contain a supply of filling and provided with a side delivery-eye, and a normally closed thread-retaining leader in front of the delivery end of the filling-supply, through which leader the thread from the supply draws to be delivered, and means on the shuttle to automatically direct the thread from the leader to the delivery-eye of the shuttle.

25. A shuttle for automatic filling-replenishing looms, adapted to contain a supply of filling and provided with a side delivery-eye, threading means on the shuttle, including a

longitudinal thread-passage, a transversely-movable retainer to extend over and close the entrance end of the passage, a spring to normally maintain the retainer in position to 5 form an eye-like entrance for the passage, and means to direct the filling-thread automatically from the passage to the delivery-eye.

26. A shuttle for automatic filling-replenishing looms, adapted to contain a supply of 10 filling and having mounted upon it thread-delivering means, said means including a leader in front of the delivery end of the filling-supply and having an open top, to admit the thread to the leader, a pivotally-mounted closure for the top of the leader, to retain the thread positively therein, and a spring-finger mounted on the shuttle and eccentrically connected with the closure, to normally hold it in position to close the leader.

27. A threading device for loom-shuttles, consisting of a block having a longitudinal thread-passage therein the side walls having forward extensions at their tops, said extensions overlapping with a clearance between 25 them, at the outer end of the passage, a horn extending from one of said extensions to the bottom of the passage at its front end, and a finger-like retainer pivotally mounted on one wall and movable transversely of the passage at its inner end, to bridge the same, the walls having oppositely-located slots therein to receive and permit pivotal movement of the retainer.

28. In a loom provided with automatic filling-replenishing mechanism, a shuttle adapted to contain a supply of filling and having a side delivery-eye, thread-delivering means on the shuttle, including a normally closed leader through which the thread from the 40 supply draws to be delivered, and devices to direct the thread to the delivery-eye, and means partly mounted on the shuttle and partly movable with the replenishing mechanism, to open the leader when a fresh supply of filling is inserted in the shuttle.

29. In a loom provided with automatic filling-replenishing mechanism, a shuttle adapted to contain a supply of filling and having a delivery-eye, means to effect positive co-operation of a fresh filling-thread end with the shuttle upon change of filling, and while the shuttle is at rest, to insure free delivery of the thread, and separate means operative upon movement of the shuttle to automatically direct the thread to the delivery-eye.

30. In a loom provided with automatic filling-replenishing mechanism, a shuttle adapted to contain a supply of filling and having a normally closed leader and a side delivery-eye, means to automatically effect the admission of the fresh filling-thread into the leader upon filling-replenishing and while the shuttle is at rest, to insure free delivery of the thread, and separate means dependent upon the movement of the shuttle to automatically direct the thread from the leader to the delivery-eye.

31. A shuttle for looms, having an opening for the reception of a filling-carrier, and a side delivery-eye, a longitudinal thread-receiving 70 passage in alignment with the axis of the filling-carrier and having a normally closed entrance adjacent and in front of the tip of the filling-carrier, means to open the entrance to receive the thread, means to direct the thread 75 from the passage to the delivery-eye, and a device to support the thread in the passage substantially in a horizontal plane intersecting the axis of the filling-carrier.

32. A shuttle for automatic filling-replenishing looms, having an opening to receive a filling-supply, means located at the front end of said opening to receive and direct the filling-thread in substantial axial alignment with the filling-supply, and a thread-retaining, 85 normally operative closure for said means, movable transversely to the longitudinal axis of the shuttle.

33. A shuttle for looms, having an opening to receive a filling-supply, and a side delivery-eye, a longitudinal thread-receiving passage the side walls whereof are forwardly extended at their tops to present extensions at the outer end of the passage, the extremities of the extensions overlapping with an inclined 95 clearance therebetween, a device normally operative to close the inner end of the passage and thereby form a thread-leader in front of and substantially in axial alignment with the filling-supply, means to move said 100 device to open the passage, and means to direct the thread from the passage to the delivery-eye.

34. A loom-shuttle adapted to contain a supply of filling and having a longitudinal 105 thread-receiving passage in its delivery end, said passage being contracted at its inner end to form a thread-entrance, a closure movably mounted at the contracted part of the passage to span the same and complete the continuity of the thread-entrance, the latter being located in front of and substantially in axial alignment with the filling-supply, means to move the closure to open the thread-entrance, and means to normally retain said 115 closure in operative position.

35. In a loom provided with automatic filling-replenishing mechanism, a shuttle adapted to contain a supply of filling, a normally closed leader in front of and substantially in 120 alignment with the longitudinal axis of the filling-supply, and means to temporarily open the leader to receive the thread of the fresh filling-supply when the latter is inserted in the shuttle.

36. In a loom provided with automatic filling-replenishing mechanism, a shuttle adapted to contain a supply of filling, means on the shuttle in alignment with the longitudinal axis of the filling-supply to receive and 130 completely surround the thread between the latter and the replenishing mechanism, and a device to automatically open said means upon filling replenishing, to receive the

thread, whereby the latter is drawn off the supply in substantial alinement with its axis.

37. In a loom provided with automatic filling-replenishing mechanism, a shuttle adapted to contain a supply of filling, a device on the shuttle to positively engage the filling-thread between the replenishing mechanism and the delivery end of the fresh supply and hold it substantially in axial alinement with the latter, and means to effect engagement of the thread by said device when the replenishing mechanism operates.

38. In a loom provided with automatic filling-replenishing mechanism, a shuttle adapted to contain a supply of filling, and provided with a leader adjacent the delivery end of the filling-supply and intersected by the longitudinal axis thereof, and means to effect positive control of the filling-thread by said leader when the shuttle is provided with a fresh supply of filling.

39. In a loom provided with automatic filling-replenishing mechanism, a shuttle adapted to contain a supply of filling, and having a longitudinal thread-receiving passage at its delivery end, a thread-retainer to normally close the inner end of the passage, and means to temporarily retract the retainer to open the passage for entrance of the fresh-filling-thread end, return of the retainer to normal position holding the thread down in the passage to draw off from the filling-supply in a substantially axial path.

40. In a loom, a shuttle adapted to contain a supply of filling and provided with a device to deliver the thread, mechanism to automatically insert fresh filling in the shuttle, and means operative upon filling replenishing to effect positive engagement of said device with the fresh filling-thread in front of and in axial alinement with the filling-supply inserted in the shuttle.

41. In a loom, filling-replenishing mechanism, including a feeder, and a transerrer to transfer filling-carriers singly therefrom to the shuttle, a filling-end holder on the feeder, a shuttle adapted to contain a filling-carrier and provided with means to engage the filling-thread between the end-holder and the filling-carrier and maintain it in substantially axial alinement with the latter, and a device to effect engagement of said means with the thread of a filling-carrier when inserted in the shuttle by the transerrer.

42. In a loom provided with automatic filling-replenishing mechanism, a shuttle adapted to contain a filling-carrier and provided with means to engage the filling-thread between said mechanism and the filling-carrier and maintain the thread in substantially axial alinement with the latter, and a device to effect co-operative engagement of said means, and the thread of a filling-carrier when it is inserted in the shuttle by the operation of said mechanism.

43. In a loom provided with automatic filling-replenishing mechanism, a shuttle adapt-

ed to contain a supply of filling and provided with a leader through which the thread from the supply of filling is drawn to be delivered, a device on the shuttle to engage and direct the fresh filling-thread end down into the leader and to normally close the latter, and means to move said device to open and close the leader upon the actuation of the replenishing mechanism, whereby the fresh-filling-thread end is inserted in and positively retained in the control of the leader.

44. In a loom, a running shuttle adapted to contain a supply of filling and provided with a normally closed leader through which the thread from the said supply draws to be delivered, mechanism to automatically provide the shuttle with filling, and means to open said leader to receive the thread end of the fresh filling-supply.

45. In a loom, a shuttle adapted to contain a supply of filling and provided with a normally closed leader through which the thread from the said supply draws to be delivered, mechanism to automatically provide the shuttle with filling, and means controlled by or through the operation of said mechanism to open said leader to receive the thread end of the fresh filling-supply.

46. In a loom provided with automatic filling-replenishing mechanism, a shuttle adapted to contain a supply of filling and provided with a threading device having a normally closed entrance through which the thread draws from said supply, and means to temporarily open the latter to receive the thread end of the fresh filling-supply.

47. In a loom, a shuttle adapted to contain a supply of filling, a normally closed leader on the shuttle adjacent the tip end of the filling-supply and through which the thread from the said supply draws to be delivered, mechanism to automatically provide the shuttle with filling irrespective of the condition of the leader, and means operative upon actuation of said mechanism to temporarily open the said leader to receive the thread end of the fresh supply of filling.

48. In a loom provided with automatic filling-replenishing mechanism, a running shuttle adapted to contain a supply of filling and provided with threading means including a thread-receiving passage having a normally closed entrance through which the thread from the supply draws to be delivered, and means to positively open and close the entrance upon filling replenishing, to thereby admit to and retain in said entrance the thread end of the fresh supply of filling with which the shuttle is provided.

In testimony whereof I have signed my name to this specification in the presence of two subscribing witnesses.

JONAS NORTHRUP.
